CLAIM

The ornamental design for a wireless mobile sensor, as shown and described.

DESCRIPTION

FIG. 1 is a perspective view of the wireless mobile sensor according to the design;

FIG. 2 is a front elevational view of the wireless mobile sensor of Figure;

FIG. 3 is a rear elevational view of the wireless mobile sensor;

FIG. 4 is a left side elevational view of the wireless mobile sensor;

FIG. 5 is a right side elevational view of the wireless mobile sensor;

FIG. 6 is a top view of the wireless mobile sensor; and,

FIG. 7 is a bottom view of the wireless mobile sensor.
